UNITED STATES PATENT OFFICE.

ALFRED H. KUDLICH, OF LYNN, MASSACHUSETTS, ASSIGNOR TO GENERAL ELECTRIC COMPANY, A CORPORATION OF NEW YORK.

CORE-BOX.

No. 902,304.

Specification of Letters Patent. Patented Oct. 27, 1908.

Application filed April 4, 1908. Serial No. 309,766.

To all whom it may concern:

Be it known that I, ALFRED H. KUDLICH, a citizen of the United States, residing at Lynn, county of Essex, State of Massachusetts, have invented certain new and useful Improvements in Core-Boxes, of which the following is a specification.

The present invention relates to core boxes, and has for its object to provide a box by means of which a plurality of separately formed articles, such for example as buckets for elastic-fluid turbines, can be accurately embedded in a core, and this at a minimum cost and with the type of help usually available in a foundry.

Owing to the special requirements of elastic-fluid turbines, great accuracy is required in the formation of such cores. The buckets must be properly aligned in a longitudinal direction, and for axial-flow machines the ends must be located in arcs of circles and must also occupy the same plane so that one will not project laterally beyond the others on either side. The pitch distance between buckets, whatever it may be, must be carefully preserved at both ends. Again, the buckets in the core must occupy such positions that the entrance and exit angles conform exactly to certain theoretical requirements which need not be here specified. The relation of the buckets for one row differs from that of every other row, and in addition vary somewhat in length and cross-sectional area, all of which increases the cost and difficulties of construction.

It is of the utmost importance that the core-box be of such a construction as to enable the average core-maker to turn out accurately made cores of uniform quality in a minimum amount of time, and this without waste of material or imperfect results.

In the accompanying drawing is shown a core-box illustrating one of the embodiments of which the invention is capable, wherein

Figure 1 is a view in side elevation of a core-box with certain parts broken away to show the interior; Fig. 2 is a plan view of the box showing it partially filled with core-making material; Fig. 3 is a cross section of the core-box; and Fig. 4 is a perspective view showing the guides and space-blocks for the buckets.

1 represents the base of the box to which end pieces 2 and 3 are permanently secured.

4 and 5 are side pieces adapted to engage

the flat surfaces of the base and end portions and with them form a receptacle to receive the buckets or other articles to be embedded in the core, and are held in place by end clamps 6 and 7. The form of the clamp can be varied to suit the requirements. The position of the sides is located by the pins 7^a which also assist in holding them.

In the present illustration the box is intended for making cores containing buckets for elastic-fluid turbines, the said buckets being radially disposed with the ends occupying arcs of circles. The pitch distance between the buckets must be carefully preserved, as well as the entrance and exit angles of the buckets one to the other. The end portions 2 and 3 are recessed at four points to receive the segmental guides 8 and 9. Two of these recesses are formed on one side of the end pieces and the other two on the other side. The guide consists of a rectangular piece of metal of segmental form and is provided with notches or grooves 10 extending radially. The pitch of these grooves is the same throughout the guide 9, and the pitch of the grooves in the guide 11 corresponds therewith. The pitch of the grooves in the lower guide 8 and in the corresponding guide 12 located on the back side may be the same as that of the upper guides 9 and 11 so that the shape of the space between the buckets will be the same at the upper end as at the lower end, or the pitch may be somewhat less so that the buckets will occupy truly radial positions and have the same center.

In order to use the box for right- and left-hand buckets, the guides 8, 9, 11 and 12 are provided with duplicate sets of grooves 13', one set being in operation at a time. This is readily accomplished by providing the guides with a set of grooves on each side, as shown in plan in Fig. 2 and in perspective in Fig. 4.

The guides are held in place by the side walls of the recesses in the end portions 2 and 3 of the box, and their longitudinal position is determined by pins 13 that enter holes therein. They are prevented from coming out of the recesses by the side plates 4 and 5.

In order to prevent the core material from covering the ends of the buckets that are to be cast into the base while the core is being formed, combined filler and space-blocks 14,

15 and 16 are provided. The blocks 14 and 16 are located at the ends and engage the outside buckets and the ends 2 and 3 of the box. The blocks 15 are situated between the buckets and conform in shape on opposite sides to the walls of the buckets as shown in Fig. 4. These blocks are also retained in position partly by the longitudinally extending strips 17 that project over the shoulders formed on the blocks and are secured to the lower guides by screws 18, Fig. 3.

The box is used in the following manner, assuming that its parts are all separate. 15 The base and end portions being united are mounted upon a suitable bench or table, and the guides 8, 9, 11 and 12 mounted in place. The buckets 19 are then slipped into place one after the other through the notches 10 20 in the guides, and between the blocks 14, 15 and 16 which were previously placed in the lower portion of the box while the guides 8 and 12 were being mounted in position. After the buckets are in place and properly 25 aligned with their inner ends resting on the upper convex surface of the base 1, the side pieces 4 and 5 are mounted in place and afterwards held by the end clamps 6 and 7. The core-maker then places the box in a convenient position and throws handful after 30 handful of core material in between the buckets. He then takes a stick and rams the material between the buckets until it has the proper degree of hardness. If the buckets do not extend to the top of the box it is 35 customary to fill the space between them and the top of the box with core material which is leveled off after being properly rammed. The box is then turned over on its side and 40 the clamps 6 and 7 and side 5 removed. The upper guide 9 is then removed and the space formerly occupied thereby filled with core material, and properly packed. If it is desired to strengthen the core by the introduction of wires, they are inserted in said space 45 before it is completely filled. The guide 8 is then removed. After this is done, the surface of the core is smoothed off and the core-box covered by an iron plate and turned 50 over bodily to present the opposite side. The side 4 is then removed to expose the core, after which the guide 11 is removed and the space filled with core material. The guide 12 is then removed and the space filled. 55 Next the base and ends are removed and the space-blocks 14, 15 and 16 taken out. When this is done, the ends of the buckets will project from the core by an amount corresponding to the depth of the space-blocks. By 60 varying the depth of the space-blocks the length of the buckets exposed beyond the core can readily be varied. The final step is to place the core and the supporting iron plate in an oven and bake it.

65 In accordance with the provisions of the

patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,— 75

1. A core-box comprising a receptacle to receive the core material having removable guides arranged in a plurality of pairs to space a series of articles to be embedded in the core and hold them adjacent each end by 80 their opposite edges.

2. A core-box comprising a receptacle to receive core material for forming a core with a group of articles embedded therein, said receptacle having guides for spacing 85 and holding the articles which engage their edges intermediate their ends, and removable guiding means for the ends of the articles which when removed leaves said ends projecting from the core.

3. A core-box comprising a receptacle to receive core material for forming a core with a group of articles embedded therein, said receptacle having removable guiding devices which engage the opposite edges of 95 the articles adjacent one set of their ends and a removable guiding device for the other ends of the articles, said devices spacing and holding the group of articles in position in the receptacle.

4. A core-box comprising a receptacle to receive the core material, guides having grooves to receive the edges of the articles to be embedded in the core to preserve their alignment, and means for preventing the 105 core material from covering the ends of said articles while the core is being formed.

5. A core-box comprising a receptacle to receive the core material, guides arranged to receive and hold the articles to be embedded in the core by their edges, and removable blocks which are located between the ends of 110 said articles so that the ends thereof will be exposed when the core is completed.

6. A core-box comprising a receptacle to receive the core material, guides arranged in pairs on each side of the articles to be embedded in the core, which engage said articles and hold them by their edges while the core is being formed, and means for preventing the core material from covering the ends of the articles which are to be united by 115 a casting.

7. A core-box comprising a base, recessed end portions and sides, removable guides 125 located in the recesses and between the ends and sides, which engage and hold the articles to be embedded in the core, and spacers located between the ends of said articles.

8. A core-box comprising a base, end and 130

side portions, removable guides having sets of grooves on opposite sides, each set arranged to receive the edges of the articles to be embedded in the core and hold them in alinement, one set being for one kind of articles and the other for a different kind, spacers located between the ends of the articles to be united by a casting, and other spacers located between the said articles and the end portions of the box.

9. A core-box comprising a base, end and side portions, removable guides arranged in pairs on each side of and engaging the articles to be embedded in the core and suitably spaced apart, spacers located between the ends of the said articles, and means carried by the guides for holding the spacers in position.

10. A core-box comprising a base having one of its surfaces formed on the arc of a

circle, which acts as a stop for the articles to be embedded in the core, end and side portions, guides arranged in pairs on opposite sides of said articles to hold them in place, and spacers which rest on the curved 25 surface of the base and are situated between the ends of the said articles.

11. A core-box comprising a base, end and side portions, guides for holding the articles to be embedded in the core by their edges 30 pins for locating the longitudinal position of the guides, and filling pieces situated between the ends of the said articles.

In witness whereof, I have hereunto set my hand this 27th day of March, 1906.

ALFRED H. KUDLICH.
